UNITED STATES PATENT OFFICE.

NATHAN OTTO RICHMAN, OF CLEVELAND, OHIO.

SPOOL-RACK.

1,345,883.

Specification of Letters Patent.

Patented July 6, 1920.

Application filed August 20, 1919. Serial No. 318,683.

To all whom it may concern:

Be it known that I, NATHAN OTTO RICHMAN, residing at Cleveland, in the county of Cuyahoga and State of Ohio, have invented a certain new and useful Improvement in Spool-Racks, of which the following is a full, clear, and exact description, reference being had to the accompanying drawings.

10 This invention relates to spool racks, which are used to hold spools of thread of various kinds or sizes for the convenience of sewing operators in clothing manufacturing or similar establishments.

15 One object of this invention is to provide a spool rack that is convenient to use in the handling of various kinds or sizes of thread and whereby the danger of soiling or tangling the thread is reduced to a minimum.

20 Another object is to provide means permitting rapid interchange or replenishment of the spools contained in the rack and at the same time prevent surreptitious or unauthorized removal of spools of thread.

25 Still another important object is the attainment of an extremely simple and compact construction whereby the device may be manufactured by few operations and from stock material of low cost.

30 In accomplishing the objects above noted, and others that will be apparent as the description proceeds, I have provided certain improved details of construction, a preferred form of which is illustrated in the accompanying drawings forming a part of this specification, the essential characteristics of the invention being set out in the claims. In the drawings, Figure 1 is a side 35 elevation of a spool rack constructed according to my invention; Fig. 2 is a front elevation of the same; Fig. 3 is a broken sectional view on the line 3—3 of Fig. 2 showing the connections between the supporting frame 40 and the locking cover; Fig. 4 is a fragmentary sectional view showing the connection between the supporting post and the spool holding frame; and Fig. 5 is a side elevation showing a modified arrangement 45 of the spool holder proper on its support.

50 Referring in detail to the parts shown in the drawings, I provide a base 1 from which rises a post 2. This post is shown as embraced by a sleeve 3 to which is attached the spool holder proper consisting of an open frame or box F in which is mounted a plu-

rality of spool holding spindles 10. A locking cover 14 closes the frame and secures the spools in position therein.

55 The base 1 is adapted to be fastened in any suitable manner to a table, bracket or other support, for example by screws as illustrated, and is preferably provided with a central boss adapted to receive the threaded end of the post 2, preferably tubular and firmly secured to the base by a lock nut 1^a as shown in Fig. 1.

60 The upper end of the post 2 is shown as provided with a pin 5 which engages notches or slots 4 in the end of a sleeve 3 carrying the spool holder proper, whereby the latter is swiveled on the post or standard 2.

65 As stated, the spool holder is preferably constructed of sheet metal in the form of an open frame or box F having a vertical wall 6 and top and bottom walls 7 and 8 respectively all integrally connected, and a separable locking cover 14 suitably attached to the top and bottom walls. As shown in 70 Figs. 1 and 4, the bottom wall 7 is provided with a centrally located opening through which is inserted the upper end of the sleeve 3. This end of the sleeve is preferably 75 threaded as at 11 and rigidly secured to the wall 7 of the frame F by suitable lock nuts 80 12 and 13, embracing the upper and lower sides of the wall 7.

85 Rigidly mounted in the wall 6 is a plurality of spindles 10 arranged preferably in vertical rows in staggered relation as shown 90 clearly in Fig. 2. These spindles are adapted to receive and support various kinds and sizes of spools of thread to be used by the operator. The spindles are shown as having rounded outer ends 10^a to prevent catching or tangling of the loose ends of the several threads, and are preferably provided with reduced inner ends 9 which fit openings punched or drilled in the wall 6, and which ends may then be headed over as shown at 95 100 24 in Fig. 1.

105 A cover 14 is provided for the frame 6 and consists of a plate having a tongue 15 of reduced width at its lower end adapted to be inserted in a slot 16 on the front portion of wall 7, and which tongue is bent at right angles to form a hinge as shown in Fig. 3. This cover plate when in place is parallel with the wall 6 and is positioned therefrom a distance slightly greater than the length of the spindles 10 so that a space is left between the rounded ends of the spin-

dles and the cover plate whereby the threads may pass the spindles of adjacent spools without danger of being wound thereon or becoming tangled with each other. The 5 upper end of the cover plate 14 is slotted at 17 to receive tongue 18 extending from the forward portion of upper wall 8. The tongue 18 is itself slotted at 19 to receive the locking bolt 20 of a suitable key lock 21 mounted in an opening 26 in the cover plate and secured therein by fastening means co-operating with flanges on said lock casing and with the portions of the cover plate 14 adjacent the opening 26.

10 I prefer to provide the frame F with openings 30 in each wall 6 and 7 so that it may be mounted on the sleeve 3 in either vertical or horizontal position as desired, but it is obvious that if the device is to be 15 used in one position only, the opening in the wall which is vertical in that position may be omitted.

15 The operation of the device is clear from the above description. As an illustration of its use, the spool holder is filled with spools of thread that may be needed by a sewing machine operator, and the cover is then locked in position. By means of the staggered arrangement of the spools a maximum 20 number may be within easy reach of the operator and the swiveled and slotted construction at 3, 4, affords access to each row of spools with equal facility. By supporting the spindles 10 in the frame wall 6 only, 25 necessity for accurate and tedious adjustment of the cover 14 is obviated and the provision of the locking means 21 prevents unauthorized or surreptitious removal of the spools of thread.

30 40 Having thus described my invention, what I claim is:

1. In a spool rack, a spindle supporting frame, and a base, tubular members secured to the frame and base respectively, said tubular members engaging each other in rotatable relation and retained in adjusted positions by a projection on one member engaging a recess in the other.

45 50 2. In a spool rack, a spindle supporting frame and a base, a tubular member secured

to the base having laterally extending projections and a second tubular member secured to the frame adapted to be received in rotatable relation with the first named tubular member and having recesses co-operating with said projections for retaining said frame in adjusted position.

55 3. In a spool rack, a base, an upright post supported in said base, a sleeve mounted on said post having one end notched to co-operate with a pin in said post and the other end threaded to receive a frame secured to said sleeve by nuts engaging said threads, a plurality of spool receiving spindles mounted in said frame and a cover on said 60 frame to prevent unauthorized removal of spools mounted on said spindles.

65 4. In combination, a frame having a spool supporting spindle, a standard, and means within said frame whereby it may be rotatably mounted upon the standard to support the spool in either horizontal or vertical position.

70 75 5. In combination, an upright supporting member, a spool holding frame, a connecting member rotatably mounted on said upright member, and means within the side and end of said frame whereby the latter may be secured to the connecting member to support the spool in either vertical or horizontal position.

80 85 6. In a spool holder, a hollow frame comprising a plate having ends bent at right angles thereto, a spindle mounted in said plate between said ends and a second plate having a tongue and slot connection at one end with said plate, the tongue being bent at right angles after passing through the slot, and a padlock connection at the other end.

90 95 7. In a spool holder, a frame comprising a plate having ends bent at right angles thereto, a spindle secured at one end to said plate, and a cover plate secured to said bent ends, the junction at one end comprising a bent tongue and slot connection.

In testimony whereof, I hereunto affix my signature.

NATHAN OTTO RICHMAN.
